SUCTION CLEANER

Harry B. White, Canton, Ohio, assignor to The
Hoover Company, North Canton, Ohio, a cor-
poration of Ohio

Application January 7, 1933, Serial No. 650,596

5 Claims. (Cl. 285—129)

This invention relates to suction cleaners, and more particularly to clamping means for detachably attaching to the outlet of the suction cleaner the dust bag, or similar means, for filtering and 5 retaining the dust which is drawn through the cleaner by the air currents. It is a common practice to provide such a dust bag with a rigid ring to which the mouth of the bag is permanently secured, such ring being detachably secured to a 10 flange on the outlet of the cleaner, it being necessary that the parts be held in close engagement to prevent the escape of dust.

One of the objects of the invention is to provide a clamping structure for this purpose which will 15 be efficient and durable, and which can be readily operated. Another object of the invention is to provide such a structure having a minimum of protruding parts, and having no parts which will engage with and wear the bag. A still further 20 object is to provide such a structure which is carried entirely by the cleaner outlet, and which will resiliently but positively hold the parts clamped together. Still further objects of the invention 25 and features of novelty will be apparent from the following specification, describing a specific embodiment of the invention which is shown in the accompanying drawings in which:

Fig. 1 is a side elevation of a suction cleaner, showing an embodiment of the invention, parts 30 of the handle and dust bag being broken away;

Fig. 2 is an enlarged view in horizontal section taken on the line 2—2 of Fig. 1;

Fig. 3 is an enlarged fragmentary view in cross-section taken on the line 3—3 of Fig. 2;

Fig. 4 is a fragmentary view in cross-section 35 taken on the line 4—4 of Fig. 2;

Fig. 5 is an enlarged fragmentary view in longitudinal section, similar to Fig. 2, but showing the parts in disengaged position;

Fig. 6 is an enlarged view in elevation of the 40 cleaner outlet taken on the line 6—6 of Fig. 5;

Figs. 7 to 15 are detailed views of the various 45 parts; and

Fig. 16 is a view in transverse section taken on 50 line 16—16 of Fig. 1.

The invention is herein shown as embodied in a suction cleaner, as illustrated in Fig. 1, having a main body 11 provided with a downwardly directed nozzle 12 through which air is drawn from 55 the carpet, or other floor coverings, by a fan located in the main body 11 and operated by a motor 13, the air and dust being discharged rearwardly through an outlet 14 which is provided with a flat circumferential flange 15. The cleaner as a whole is mounted upon wheels 16 which

hold the nozzle 12 spaced slightly above the floor covering, and a handle 17 is pivoted to the cleaner body to facilitate directing the cleaner over the floor covering. Suitable means 18 are provided for adjusting the height of the rear wheels 16, 60 thereby adjusting the nozzle 12 to and from the floor covering, and a suitable dust bag 19 is permanently attached to a dust bag ring 20 of the same general size and contour as the flange 15 to which it is to be detachably secured. Such parts 65 are of usual construction, and the present invention relates to the means for detachably securing together the flange 15 and the dust bag ring 20.

A tubular operating member 21, shown in detail in Fig. 10, is rotatably mounted in a bore 70 22 through the flange 15, and is held from longitudinal movement therein by a flange 23 at its rear end which is preferably received in a counterbore in the flange 15, so as to be flush with the rear face thereof. To the front end of the 75 tubular member 21 an operating lever 24 is secured by a set screw 25, or similar means, and if desired the end of the member 21 may be upset, as shown at 26, against the outer face of the lever. A spring washer 27 is preferably provided between the rear face of the lever 24 and the front face of the flange 15, such washer 80 preferably being provided with a notch 28 by which it is anchored against rotation. A cam slot 29, which is preferably helical, is formed in the tubular member 21 and is preferably continued at one end to pass through the rear face of the flange 23. A slot 30 is formed through the flange 15, communicating with the bore 22, and is preferably lined by a wear member 31, of general U- 85 shape, as shown in detail in Fig. 15, which may also, if desired, have an integral bent up lug or portion 32 for engagement in the notch 28 to prevent rotation of the spring washer 27.

A rod 33 is reciprocatably mounted in the flange 90 15, passing through the operating member 21, and having a radially projecting pin 34 which passes through the slot 29 in the tubular member 21 and into the slot in the wear member 31. It will be evident that the rod 33 is thus held 100 from rotation, but can slide longitudinally and that, by reason of the engagement of the pin 34 in the slot 29, rotation of the tubular member 21 will project and retract the rod 33 a predetermined distance in each direction relative to 105 the face of the flange 15. The front end of the rod 33 is preferably provided with an enlarged head 35, for engagement with the inner end of set screw 25, whereby rearward movement of the rod 33 will be limited and accidental removal of 110

the rod 33 from the rearward end of tubular member 21, when the ring 20 is not in place, will be prevented. Movement of the rod 33 in the opposite direction will obviously be limited by 5 the engagement of the pin 34 with the front end of the slot 29.

The rearward end of the rod 33 is preferably provided with a resilient head in the form of a cup-shaped member 36 in which there are received 10 a coil spring 37 and a washer 38 which is riveted or otherwise secured to the end of the rod 33. A shoulder 39 is provided on the rod 33 to limit the movement of the cup-shaped member 36 under the action of the coil spring 37.

15 It will be understood that there are two similar clamping means, preferably located at diametrically opposite points on the flange 15, only one having been described in detail. To secure air tight fitting of the ring 20 and the flange 20 15, it is also preferable that one of these parts be provided with a suitable annular channel 40 in which a gasket 41 of sponge rubber, or similar material, is located. The ring 20 is provided with laterally projecting ears 42 having downwardly 25 opening slots 43 therein, so that the ring may be moved downwardly upon the rods 33, and it is preferable that the face of the ring 20 be slightly cupped, as shown at 44, to receive the resilient head 36, and thereby prevent relative 30 accidental shifting of the ring relative to the flange 15. The bag 19 may be secured to the dust bag ring 20 in any suitable manner, but is herein shown as having a clamping band 45 sewed in the hem of the bag and contracted by 35 a bolt 46 against an internal flange 47 on the ring 20.

It will be evident that the two rods 33 with 40 their resilient heads in the position shown in Fig. 5 will project rearwardly from the flat flange 45 and that the bag ring 20 may be readily engaged with the flange 15 and slid downwardly upon the rod 33 and, upon rotation of the levers 24, the heads 36 will be retracted toward the flange 15 to clamp the ring 20 thereto. Because 45 of the springs 37, the ring 20 will be resiliently but forcibly held in place, and any shifting of the ring 20 will be prevented by the engagement of the heads 36 in the cups 44. It will also be apparent that, by reason of the slight projection 50 of the heads 36 from the rear face of the ring 20, any danger of wear of the bag 19 by rubbing against the clamping members will be prevented, and that the clamping devices as a whole will 55 present no objectionably protruding parts and will have a neat appearance.

While one embodiment of the invention has been illustrated and described, it will be understood that many changes in the details of structure may be made within the scope of the invention defined by the following claims.

I claim:

1. A clamping device for detachably clamping together a pair of members, comprising a slider mounted for reciprocation in one of said members and having an abutment for engagement with the outer face of the other of said members, a manually operable element rotatably associated with said slider, said slider and said element being carried by said first member and having a helical slot and pin connection with each other whereby rotation of said element will reciprocate said slider, and means on said first member and said slider cooperating to prevent relative rotation.

2. A clamping device for clamping together a pair of members, comprising a rod slidably mounted in one of said members and held from rotation relative thereto, a tubular element rotatably carried by said member and surrounding said rod, said tubular element having a helical slot therein and having a portion accessible for rotation manually, said rod having a projection extending through said helical slot and having an abutment for engagement with the other of said members.

3. A clamping device for clamping together a pair of members, comprising a slider mounted for reciprocation in one of said members, a manually operable element carried by said member and rotatably associated with said slider, said slider having a projection thereon and said element having a cam surface thereon engaging said projection to reciprocate said slider, and an abutment member resiliently mounted on said slider for engagement with the outer face of the other of said members.

4. A clamping device for clamping together a pair of members, comprising a slider mounted for reciprocation in one of said members, a manually operable element carried by said member and rotatably associated with said slider, said slider having a projection thereon and said element having a cam surface thereon engaging said projection to reciprocate said slider, an abutment head resiliently mounted on said slider for engagement with the outer face of the other of said members, and means on said slider for limiting the movement of said head relative to said slider.

5. A clamping device comprising a base, a rod slidably mounted in said base, a tubular element surrounding said rod and rotatably mounted in said base, said element being held from endwise movement relative to said base and having a cam slot therein, said base having a slot therein, a projection on said rod passing through said cam slot and engaging in the slot in said base to prevent rotation of said rod relative to said base, an enlarged head on the free end of said rod, and means for rotating said tubular element to reciprocate said rod a definite distance in either direction.

HARRY B. WHITE.
